UNITED STATES PATENT OFFICE

ROY C. AYLOR, OF BRIGHTWOOD, VIRGINIA

CHICKEN TRANSPORTATION COOP

Application filed January 19, 1929. Serial No. 333,593.

This invention relates to improvements in chicken transportation coops, particularly in the means for efficiently closing off the opening in the coop through which the chickens 5 are either deposited within the coop or removed therefrom.

An object of this invention is to provide a chicken container comprising a frame and a plurality of rods held in spaced relationship 10 to each other within the frame, and having an opening in the coop through which the chickens may be placed within or removed 15 from the coop, the door for closing the opening being constructed and mounted upon the coop in such a manner that it will function to maintain a constant spaced relationship 20 from the upper and lower edges of the opening.

A prime object of this invention is to provide 25 a chicken coop having a door therein slidably and rotatably mounted upon a rod member of the coop, and resilient means for maintaining the upper and lower edges of the door in desired spaced relationship from the upper and lower edges of the receiving 30 opening in the coop, also, a bolt means comprising one of the rod members of the coop and a groove in the door for receiving the end of the rod member, thereby providing a 35 means for holding the door in closed and interlocked position. The door may only be opened by compressing the resilient means, thereby releasing the bolt from the groove and allowing the door to swing free.

Other objects of this invention will appear 40 from the following detailed description of the device and as disclosed in the single sheet of drawings which is herewith made a part of this application.

In the drawings—

Figure 1 illustrates a perspective view of a portion of the chicken transportation coop disclosing the opening, and the door in closed position therein.

Figure 2 represents a vertical sectional view of a portion of the chicken coop disclosing the opening therein and the door in operative relationship thereto.

Figure 3 illustrates a sectional view of Figure 2, taken along line 3—3.

Figure 4 represents a perspective view of the door for the chicken coop.

Figure 5 illustrates a modification of this invention, particularly in the bolting means for holding the door in closed and fixed relationship to the opening in the coop. 55

Figure 6 represents a modification of this invention disclosing a means for holding the door in spaced relationship from the upper and lower edges of the opening together with 60 a means for holding the door in closed relationship to the coop.

Figure 7 is a fragmentary detail view.

As one modification of this invention it is preferred that numeral 1 designate the frame 65 of a chicken coop having connected therewith in spaced relationship a plurality of rods or slats 2, made of any suitable material such as wood. In one of the sides of the chicken coop, as clearly disclosed in Figures 1 and 2, 70 an opening 3 is formed through which the chickens may be either placed within the coop or extracted therefrom.

The opening 3 is preferably bounded at the top and bottom by cross frames 4 and 5, into 75 which the rods 2 are adapted to extend. The other two sides of the opening 3 are bounded by rod members 6 and 7. A door member 8, made of any suitable material such as wood, is provided for the opening 3, and arranged 80 at one end to be pivotally and slidably mounted on the rod member 7, as clearly disclosed in Figure 2, through an opening 9 in the door 8.

The free end of the door 8 is provided with 85 a slot 10, which cooperates with the rod 6, which in turn contacts with the extension 11 when the door 8 is closed. Spring tension members 12 and 13 are loosely mounted upon the rod 7 between the upper edge of the door 8 and the cross frame 4, and the lower edge of the door 8 and the cross frame 5, in order to retain the desired spaced relationship between the upper and lower edges of the door 8 and the upper and lower edges of the opening 3. 90

One of the rod members 14 is adapted to extend inwardly of the opening 3 and be received within a notch 15, formed in the lower edge of the door 8, thereby functioning to 100

firmly lock the door in closed relationship with the opening 3. It is obvious that a slight pressure on the door 8 toward the frame member 4 will function to compress the tension spring 12 and release the rod or bolt bar 14 from the groove 15, thereby allowing the door to swing outward and open.

In order to seal the door in position, an opening 16 is located therein through which the sealing member 17 may extend in cooperation with the cross frame 5, thereby providing means for assuring that the door 8 will remain in closed position until the seal 17 has been broken.

Figure 5 illustrates a modification of the means for bolting the door 8 in closed position, consisting primarily of a reversal of the means, as disclosed in Figure 2. Numeral 18 designates a bolt member made of wood or otherwise, extending from the door 8 in such a manner that it may cooperate with a slot 19 in the frame member 5. The bolt 18 may be released from the slot 19 by merely forcing the door 8 in the direction of the cross frame 4.

Figure 6 illustrates another modification of a means for holding the door in closed position as well as the upper and lower edges thereof in the desired spaced relationship from the frame cross members 5 and 4.

A locking member is provided having an attachment spacer part 20, which may be formed as a sleeve and loosely mounted upon the rod member 7, and of the desired length for allowing the predetermined space between the lower edge of the door and the cross frame 5. The attachment plate 25 is securely fastened in the frame member 5 by means of screws 21, or other suitable fastening elements. An arm portion 22 extends integrally from the spacer part 20 parallel with the cross frame 5, and is provided at the outer end thereof with an inwardly extending lug 23, adapted to be received in a detent 24, formed in the lower edge of the door 8, thereby functioning to hold the door in closed relationship when desired. The attachment may be reversed if desired.

By pressing the door against the spring 12, the lug 23 will be released from the slot 24, and the door 8 allowed to swing free of the opening 3.

This invention provides a very efficient chicken coop particularly adapted for transportation purposes, having a door arranged to close in such a manner that a desired spaced relationship may be maintained between the upper edge of the opening and the upper edge of the door, and the lower edge of the opening and the lower edge of the door.

In order to release the door from bolted and closed position, it is merely necessary to slide the door on its pivot hinge until the bolt has been withdrawn therefrom, after which the door may be readily opened, the

spring tension element being located in such a manner as to hold the door in normal position within the opening.

It will be understood that many changes and modifications may be made in the form of embodiment of this invention within the scope of the following claims without departing from the spirit thereof.

What I claim is:

1. In a coop for transporting chickens, having an opening through which the chickens may be either deposited within the coop or removed therefrom, a rod at a side of said opening, a door rotatably and slidably mounted at one end on said rod, means for securing the door comprising a bolt for holding the door in closed position, consisting of a sleeve member mounted on said rod between one edge of said door and the adjacent edge of the opening and having an arm extending therefrom, and an inwardly directed lug on the outer end of the arm, the door having an opening for receiving the lug.

2. In a chicken coop having an opening, a rod extending across said opening, a door rotatably and slidably mounted on said rod, means for fastening the door comprising a spacing member on said rod between one edge of the door and the adjacent side of the opening, means fastening said spacing member to the coop, an arm extending laterally from said spacing member, cooperating interlocking formations on the door and said arm, respectively, engageable with and disengageable from one another by sliding movement of the door along said rod when the door is in a closed position, and a spring between the opposite edge of the door and the adjacent side of the opening constantly urging the door along said rod in the direction of the spacing member.

In testimony whereof I affix my signature,

ROY C. AYLOR.
